CONTAINER OPENING DEVICES

John E. Walsh, Beverly, Mass., assignor to United Shoe Machinery Corporation, Flemington, N.J., a corporation of New Jersey

Filed May 10, 1960, Ser. No. 28,039

5 Claims. (Cl. 220—52)

This invention relates to opening devices for covers of metallic containers which utilize tear strips and opening keys. One such opening device has a tear strip lying in the plane surface of the cover and extending around the cover just inwardly of its perimeter with the key permanently secured as a second class lever to one end of the tear strip. The end to which the key is attached is in the form of an inwardly projecting tab. To open the cover, the inner end of the key is lifted pivoting it about the other end as a fulcrum which pulls up on the tab and breaks the end of the tab from the container. Thereafter, the remainder of the tab and the tear strip is removed by either a continuous pull on the key or by turning the key bodily about its own axis. In the latter operation the key is first pivoted upwardly about its fulcrum until the lifting end turns over and projects beyond the outer margin of the container, whereupon the key is wound about its own axis with the tear strip forming a coil about the fulcrum end. However, on relatively small containers with diameters not much larger than the axial length of the key, the tear strip is formed with a continuous sharp curve of small radius making the accurate formation of the coil about the key difficult. This causes the coil to have a tendency to slip off the key which is obviously undesirable in that it impedes the opening process. Also in instances where the tear strip has straight runs plus sharp bends, as for example, at the corners of flat rectangular sardine cans, the strip is extremely difficult to coil and likewise has a tendency to slip off the key.

One object of this invention is to provide a cover for a metallic container having a tear strip and opening key permanently secured thereto, shaped and positioned relative to each other and to the cover so that when the strip is broken open and the key wound there is an accurate formation of coil about its end without slipping from the key.

Another object of this invention is to provide a cover having an opening key permanently secured to a tear strip which has a small radius of curvature relative to the size of the key with means on the key for controlling the formation of a coil of the tear strip material on the key as the key is turned bodily about its axis.

When the width of the key at the fulcrum end is equal to or less than the width of the inwardly projecting tab of the tear strip there is a tendency for the fulcrum to puncture the tear strip or depress it into the can which is obviously undesirable.

Accordingly, it is another object of this invention to provide a cover for a container having a tear strip and an opening key permanently secured thereto, which key is adapted to break open the tear strip without depressing it into the container.

In accordance with these objects and as a feature of this invention, there is provided a cover for a metallic container having a prescored tear strip formed in its surface and extending around the cover just inside its pe-

2

ripheral edge. The tear strip has an inwardly projecting tab or starting portion provided with a permanently secured opening key in the form of a second class lever to pry the tab from the cover. The key has a lifting portion at one end adapted to be gripped by the fingers and a fulcrum on the other end separated by a narrow intermediate portion. The key is secured to the tear strip by a spot weld intermediate of its ends. The fulcrum of the key may be either a bar extending transversely of the axis of the key or a straight edge including projecting ears, the fulcrum being of a greater width than both the tab and the intermediate portion of the key so that when the key is lifted, pivoted about the fulcrum and extended beyond the edge of the can, the tab overlies the upturned underside of the key and the ends of the fulcrum or the ears extend outwardly from beneath the tab.

The fulcrum in whatever form it may be constructed, must be located inwardly of the inner edge of the peripheral portion of the tear strip an amount equal to its own breadth (or half its circumference if it is a bar or rod) such that when the key is pivoted 180° about the fulcrum, the ends of the fulcrum or ears are still within the inner edge of the peripheral portion of the tear strip. These projecting portions of the fulcrum bar or ears then serve as guides for the formation of the coil of the tear strip as it is wound about the key, thereby assuring that the coil does not slip off the key particularly where it proceeds around sharp bends or curves having small radii. As long as the fulcrum end of the key is wider than the projecting tab of the tear strip insofar as preventing the tear strip from being depressed into the container, it is immaterial whether it is greater than, equal to or less than the intermediate and lifting portions of the key. The single requirement for preventing depression is that the fulcrum be wider than or bridge the tab of the tear strip.

The above and other features of the invention, including various novel details of construction and combinations of parts will now be more particularly described with reference to the accompanying drawings and pointed out in the claims. It will be understood that the particular cover embodying the invention is shown by way of illustration only and not as a limitation of the invention. The principles and features of this invention may be employed in varied and numerous embodiments without departing from the scope of the invention.

In the drawings,

Fig. 1 is a plan view of a circular cover for a metallic container having a tear strip and opening key embodying the invention;

Fig. 2 is a plan view of the container opening device shown in Fig. 1 with the opening key lifted and turned to the outside of the cover;

Fig. 3 is a plan view similar to Figs. 1 and 2 with the key having been rotated and a portion of the strip severed from the cover and wound on the key;

Fig. 4 is an alternative form of opening key; and,

Fig. 5 is a showing of a rectangular container cover embodying the invention.

The invention is illustrated in Figs. 1 through 3 in a circular cover 2 adapted to be secured by double-seaming or any other convenient means to the body of a container. The cover 2 is provided with a prescored tear strip 4 which is located adjacent the inner edge of the crest 6 which, after double-seaming, forms the uppermost portion of the cover. The tear strip 4 extends around the perimeter of the cover being formed by two concentric peripheral score lines 8 and 10. Contiguous with the peripheral portion of the tear strip is an inwardly projecting tab 12 which is terminated by an arcuate portion 14 of the inner score line 10. An open-

ing key 16 overlies the arcuate portion of the tab 12 and comprises a lifting end 18 in the form of a ring adapted to be gripped by the fingers, an intermediate portion 20 and a fulcrum portion 22. The fulcrum portion has a straight fulcrum edge 24 and a pair of projecting ears 26 contiguous therewith and considered together as the fulcrum member. It will be noted that the fulcrum portion of the key is of greater width than the tab 12 so that the fulcrum member (including the ears 26) extends outwardly on both sides of the projecting tab.

A spot weld 28 joins the intermediate portion of the key 20 to the tab 12 to secure the key permanently to the tab and thus making the key a second class lever.

The edge 24 of the fulcrum end of the key is spaced inwardly from the inner peripheral score line 10 an amount equal to or greater than the breadth of the fulcrum member, said breadth being defined as the dimension of the ears 26 taken axially of the key which is between the fulcrum and lifting ends.

Fig. 4 illustrates an alternative form of key wherein the fulcrum member is a bar or rod 30 of any desired cross section secured to the intermediate portion 32 of the key. The lifting portion of the key 33 may be of any configuration, flat or contoured without departing from the scope of this invention. Whether the cross section of the fulcrum bar is circular, square, rectangular or any other configuration, its left-hand end 34 must be spaced inwardly of the inner peripheral score line 10 of a cover an amount equal to at least one-half the circumference of the fulcrum bar.

The spacing of the edge of the fulcrum member, as well as the width of the member (or the ears 26), is critical as will now be apparent from an inspection of Figs. 2 and 3. When the lifting end 18 of the key is raised and the entire key pivoted about the fulcrum member 22, the arcuate portion 14 of the tab 12 is broken away from the cover. After the tab has been broken out the key may either be pulled from the cover to sever the remaining or peripheral portion of the tear strip from the cover, or the pivotal movement may be continued until the key occupies the Fig. 2 position with the tear strip overlying the then upturned undersurface of the key. Note at this time, the ears 26 or the ends of the fulcrum bar, as the case may be, project outwardly from beneath the tab but are located wholly within the inner arcuate score line 10. The key is then in position to be turned bodily about its own axis to assume, first, the solid line and then the dotted line position shown in Fig. 3 while the tear strip 4 is coiled about the intermediate portion of the key. Due to the presence of the projecting ears 26 or ends of the fulcrum bar, the coil is maintained on the key and is prevented from sliding off inwardly of the can. Winding is continued until the entire tear strip has been severed or until sufficient portions of the tear strip have been severed such that the cover can readily be removed. Should, however, the edge of the fulcrum be positioned adjacent the score line 10, after one turn the ears would be covered by the partially coiled strip and be of no value in controlling the coil.

Fig. 5 illustrates the tear strip and key secured to a cover on a rectangular or "sardine" type can. It will be evident that as the key is wound around the sharp corners 36 of the can there will be considerable tendency for the tear strip coil to slide off the key and in such applications the benefits accorded by the projecting ears or projecting ends of the fulcrum member will be most readily appreciated.

While the invention has been described as embodied in covers for metallic containers, it will be understood that it is equally applicable to covers for containers the walls of which may be formed partially or entirely of materials other than metal.

Having thus described my invention, what I claim as

new and desire to secure by Letters Patent of the United States is:

1. A cover for a metallic container having in its surface score lines defining an inwardly extending tab, a rigid class two lever adapted to break open instantaneously the inner end of the tab, said lever being located on the cover and having at one end a fulcrum wider than the inner end of the tab to bear on the cover surface on both sides of the score lines defining the tab, an intermediate portion of the lever being permanently secured only to the tab at an area adjacent the fulcrum, said lever having a lifting portion at the end opposite the fulcrum whereby when the lifting portion is raised the fulcrum end bears downwardly on the cover thereby using the full mechanical advantage of the lever to pry up the inner end of the tab and initiate the tearing out of said tab.
2. A cover for a metallic container having in its surface score lines defining a tear strip with a continuing inwardly extending tab portion, a rigid class two lever adapted to break open instantaneously the inner end of the tab, said lever being located on the cover and having at one end a fulcrum wider than the tab to bear on the cover surface on both sides of the score lines defining the tab, an intermediate portion of the lever being permanently secured only to the tab at an area adjacent the fulcrum, said lever having a lifting portion at the end opposite the fulcrum whereby when the lifting portion is raised the fulcrum end bears downwardly on the cover thereby using the full mechanical advantage of the lever to pry up the inner end of the tab and initiate the tearing out of said strip.
3. A cover for a metallic container having in its surface score lines defining a peripheral tear strip with a continuing inwardly extending tab portion, a rigid class two lever adapted to break open instantaneously the inner end of the tab, said lever being located on the cover and having at one end a fulcrum wider than the tab with at least a portion bearing on the cover surface inside the peripheral portion of the tear strip and laterally of said tab portion, an intermediate portion of the lever being permanently secured only to the tab at an area adjacent the fulcrum, said lever having a lifting portion at the end opposite the fulcrum whereby when the lifting portion is raised the fulcrum end bears downwardly on the cover thereby using the full mechanical advantage of the lever to pry up the inner end of the tab to initiate tearing out of said strip without depressing the tab into the container.
4. A cover for a metallic container having in its surface score lines defining a peripheral tear strip with a continuing inwardly extending tab portion, a rigid class two lever adapted to break open instantaneously the inner end of the tab, said lever having a lifting portion at one end, an intermediate portion permanently secured only to the tab, and at the end opposite the lifting portion a fulcrum member wider than both the tab and the intermediate portion of the lever, said fulcrum member being located on the cover to bear on the cover surface inside the peripheral portion of the tear strip and laterally of said tab portion whereby when the lever is lifted, pivoted about the fulcrum member and the lifting portion extended to the outside of the cover the tab portion is instantaneously broken open from the cover and overlies the then upturned underside of the lever with a portion of the fulcrum member extending outwardly from beneath the tab.
5. A cover for metallic container having in its surface score lines defining a peripheral tear strip with a continuing inwardly projecting tab portion, a rigid class two lever adapted to break open instantaneously the inner end of the tab, said lever having a lifting portion at one end, an intermediate portion permanently secured only to the tab, and at the end opposite the lifting portion a fulcrum member wider than both the tab and the intermediate portion of the lever, said fulcrum member being

located on the cover to bear on the cover surface on both sides of the score lines defining the tab portion and inwardly of the inner edge of the peripheral portion of the tear strip an amount at least equal to its breadth measured in a direction toward the lifting portion, whereby when the lever is lifted, pivoted about the fulcrum member and the lifting portion extended to the outside of the cover the fulcrum member is wholly inside the inner edge of the peripheral portion of the tear strip with its ends extending outwardly from beneath the tab as

guides for the formation of a coil of tear strip material when the lever is subsequently turned about its axis.
